LIGHTER

Edwin B. de Mesquita, Forest Hills, N. Y., assignor to American Safety Razor Corporation, Brooklyn, N. Y., a corporation of Virginia

Application March 26, 1949, Serial No. 1,653

Term of patent 14 years

(Cl. D48—27)

To all whom it may concern:

Be it known that I, Edwin B. de Mesquita, a citizen of the United States, and a resident of Forest Hills, county of Queens, State of New York, have invented a new, original, and ornamental Design for a Lighter, of which the following is a specification, reference being had to the accompanying drawing, forming part thereof.

Fig. 1 is a perspective view of a lighter showing my new design;

Fig. 2 is a rear elevational view thereof;

Fig. 3 is a side elevational view;

Fig. 4 is an elevational view of the side opposite to Fig. 3;

Fig. 5 is a front elevational view, the locket being shown in open position; and

Fig. 6 is a top plan view.

I claim:

The ornamental design for a lighter, as shown.
EDWIN B. DE MESQUITA.
